George A. H. H.

UNITED STATES PATENT OFFICE.

SAMUEL BONAT AND HARRY BONAT, OF NEW YORK, N. Y.

WIG.

Application filed April 15, 1922. Serial No. 553,116.

To all whom it may concern:

Be it known that SAMUEL BONAT and HARRY BONAT, citizens of the United States, residing at New York city, in the county of New York and State of New York, have invented certain new and useful Improvements in Wigs, of which the following is a specification, reference being had therein to the accompanying drawing.

10 Our invention relates to improvements in toupees or wigs, and more particularly has reference to the manner of joining or connecting the several sections thereon. Heretofore it has been the practice to mount 15 the sections of the toupee upon a backing or support of fabric, to which the hair is attached, but this is cumbersome and uncomfortable to the wearer, needlessly heating the scalp, and rendering a toupee less 20 adaptable for manipulation and dressing. According to a preferred embodiment of our invention, a toupee of say 3 sections is 25 preferably joined at the center in triangular formation, leaving the center open, and avoiding the necessity of a backing or support in the way of fabric or the like, thus reducing the weight of the same upon the head, and providing for ventilation, etc.

In accompanying drawing, we have illustrated 30 a suitable form of toupee having three sections, with the sides of the ends joining, forming a triangle open at the center where the strands or hairs are braided, securely retaining the several sections together, and after which any one of the sections 35 may be thrown over the open center in the dressing of the hair.

Referring to said drawings 1, 2 and 3 indicate the three sections of the toupee connected at their adjacent ends, as indicated 40 at 4, 5 and 6, leaving a triangular opening in the center 7, over which any one of the sections such as 3 may be laid in dressing the hair. Of course, it will be understood that modifications may be made in 45 the construction and arrangement of parts, without departing from the spirit of the invention as claimed.

We claim:

1. In a wig of the class described, several 50 sections having their adjacent ends connected, forming a central opening from which said sections extend outwardly.

2. In a wig of the class described, several 55 sections having their adjacent ends connected, forming a central opening from which said sections extend outwardly, said sections of three in number, and said opening of triangular formation.

3. In a wig of the class described, several 60 sections having their adjacent ends connected, forming a central opening from which said sections extend outwardly, said sections of three in number, and said opening of triangular formation; in a wig of 65 the class described, several sections connected at and extending outwardly from the center, said sections connected without a backing.

In testimony whereof we hereunto affix 70 our signatures.

SAMUEL BONAT.
HARRY BONAT.
